RESETTABLE CIRCUIT INTERRUPTER

Monroe Guett, Hartford, Conn., assignor to The Arrow-Hart & Hegeman Electric Company, Hartford, Conn., a corporation of Connecticut

Application July 10, 1935, Serial No. 30,722

14 Claims. (Cl. 200—116)

This invention relates to devices for manually opening and closing an electric circuit and for automatically opening the circuit upon the occurrence of a predetermined overload current.

5 More particularly this invention relates to devices of the above type which are adaptable for use with tools and small electrical apparatus in which it is only desired to have the circuit closed for a short period of time. However, the principles of this invention may be applied to devices 10 for controlling larger electrical apparatus and devices in which the circuit may be closed over longer periods.

It is an object of my invention to provide a 15 manually and automatically operable circuit interrupter of simplified construction and low cost of manufacture.

Another object of my invention is to provide an improved manually and automatically operable 20 circuit interrupter in which the circuit may not be maintained closed by holding the handle in closed circuit position during the continuance of an overload.

Another object of my invention is to provide 25 a manually and automatically operable circuit interrupter in which the manually operable means will automatically open the circuit upon removal of pressure from the actuating handle and will at the same time reset the automatic mechanism in case the circuit has been opened 30 by reason of the action of an overload current.

Another object of my invention is to make a 35 circuit breaker of the above type in which the parts may be housed within a small space without interfering with the positive and accurate operation of the device.

Other objects and advantages of my invention will appear as it is described in connection with the accompanying drawing.

40 In the drawing:—

Figure 1 is a plan view of the interior of a 45 manually and automatically operable circuit interrupter embodying the principles of my invention. In this view the parts are in the position taken when the circuit is manually opened.

Figure 2 is a view of my invention similar to 50 Figure 1 but with the parts in closed circuit position.

Figure 3 is a right end section view with the 55 section taken on line 3—3 of Figure 1 of my invention.

Figure 4 is a left end section view with the section taken along line 4—4 of Figure 1.

Figure 5 is a plan view of my invention similar 55 to Figure 1, but with the parts in the position

taken when the circuit has been automatically opened by the operation of an overload current.

Figure 6 is a perspective view of the post for mounting one circuit interrupter contact and one leg of the bimetallic member.

Referring to the drawing the circuit interrupter mechanism is mounted upon the base 10 of a two part hollow insulating casing, the cover 12 of which is removed in Figures 1, 2 and 5, to clearly show the circuit interrupter mechanism. As illustrated the casing is rectangular in shape, but obviously it may take other suitable forms. The current enters the switch through a wire terminal, denoted generally in Figure 1 by the numeral 14, which is stamped in L shape from sheet metal and has one arm 14a secured to the floor of the base 10 by rivets or other suitable means. The other arm 14b of this terminal 14 extends up at right angles to the floor of the base adjacent the left hand wall and has a threaded aperture provided in its end for the reception of a binding screw 16 by means of which a wire may be secured to the terminal. The arm 14b near its bottom is enlarged by a lateral extension 14c and has mounted upon this enlargement a contact button 18 with which cooperates a similar contact button 20 which is mounted upon the end of a resilient arm 22a of a movable contact, denoted generally in Figure 1 by the numeral 22. This movable contact 22 has another arm 22b extending substantially at right angles to the arm 22a upon the end of which is mounted a contact button 24 which is adapted to cooperate with a similar contact button 26 hereinafter more particularly described. The movable contact 22 is secured to the floor of the base 10 by a lug extending laterally from the arm 22a adjacent the juncture of the arms 22a and 22b. Thus lug 22c is bent at right angles to the plane of the arm 22a so as to lie flat upon the floor of the base 10 while the arms 22a and 22b lie in planes perpendicular to the floor of the casing part 10.

The engagement of contact buttons 18 and 20 is controlled manually as will hereinafter be described and by means of these contacts, the normal control of the circuit is effected. The engagement of the contact buttons 24 and 26 is controlled automatically by current responsive mechanism hereinafter described, so that these contacts form means for interrupting the circuit upon the occurrence of overload or abnormal conditions.

The contact button 26 is mounted upon an arm 28a extending from the central portion of

a conducting post, denoted generally by the numeral 28 in Figure 1. This post has one end turned out at right angles to it forming a foot 28b which lies upon the floor of the casing part 10 and is secured thereto by rivets whereby the post is secured in position. The top of the post has an arm 28c extending at right angles thereto for mounting one leg 30 of a current-responsive latch, denoted generally by numeral 33 in Figures 1 and 2. This leg 30 is made of bimetal so as to bend upon the passage therethrough of an overload current. The arm 28c has a finger 28d extending from the end of it, which finger passes through an aperture in the enlarged end portion 15 of the bimetallic leg 30. Metal washers 31 and 32 may be provided on each side of said enlarged end of the bimetallic leg 30 so that as the end of the finger 28d is peened over, said enlarged end of the bimetallic leg will be mounted 20 firmly upon the post 28. The other end of the bimetallic leg 30 is riveted to one end of the cross portion of an inverted T-shaped member denoted generally in Figure 3 by the numeral 34 while the other end of the cross portion of this 25 T member has riveted to it a bimetallic leg 36 similar to the leg 30 and parallel to said leg 30. This bimetallic leg 36 has its other end secured to the end of one arm 38a of a wire terminal member denoted generally in Figure 1 by the numeral 38. This arm 38a lies along the same wall 30 of the casing part 10 adjacent which the post 28 is mounted and this arm 38a is bent at right angles to the main body of the wire terminal 38. The bimetallic leg 36 is mounted upon this arm 35 38 in the same fashion as the bimetallic arm 30 is mounted upon the post 28. The main body of the wire terminal 38 lies along the wall of the casing opposite to the wire terminal 14 and has an enlargement with a screw-threaded aperture 40 in which is binding screw 40 by means of which a feed wire may be secured to the terminal. The wire terminal 38 is secured to the floor of the base 10 by screws or any other suitable means passing through a lug 38b bent at right angles to the 45 main body of the terminal.

Referring back to the T member 34 it will be noted that the leg portion 34c extends toward the wall of the casing farthest from the contacts 24 and 26 and is adapted to be engaged by the nose 50 60a of a pivoted member 60 whose function and structure is hereinafter more particularly described.

The means for causing the manual engagement of the contacts 18 and 20 will now be described. 55 The movable contact arm 22a is normally biased to open circuit position (see Figure 1) by the inherent resilience of this arm. In order to move the contact 20 into engagement with the contact 18 an L shaped operating lever denoted generally 60 in Figure 5 by numeral 42, is pivotally mounted upon a pin 44 located in the corner of the base diagonally opposite the corner in which are the contacts 24, 26. This pin 44 extends up from the floor of the base 10, and passes through the 65 central portion of one arm 42a of the operating lever. This arm 42a lies within the casing but the other arm 42b extends outside the casing for engagement by the hand of the operator. Upon the end of the inner arm 42a are mounted a pair 70 of circular insulating washers 46, one on each side of the arm 42a. These washers are secured in place by a pin 47 passing through them and through the end of the arm 42a and this pin 47 has an extension directed away from the floor of the casing part 10 against which extension presses

an end 48a of a wire spring 48 which is coiled about an extension of the pivot pin 44 and tends to bias the operating lever to open-circuit position as shown in Figure 1 by reason of the other end 48b of the spring engaging with an extension of the pivot pin 50 upon which the hereinbefore mentioned member 60 is mounted. The arm 42a is of such length that the insulating washers 46 will engage with the arm 22a of the movable contact when the operating lever 42 is depressed, as shown in Figures 2 and 5, to cause the movable contact button 20 to engage with the fixed contact button 18.

The mechanism for automatically opening the circuit upon the occurrence of an overload current passing through the device will now be described. This mechanism comprises a pair of links denoted generally in Figure 1 by numerals 60 and 62. The link or member 60 hereinbefore mentioned is pivoted upon the hereinbefore mentioned pin 50 and may be a sheet metal stamping having a nose 60a engaging with the end of the latch member 33, as shown in Figure 2, when the parts are in closed circuit position. This member 60 is biased in a clockwise direction by a 15 spring denoted generally in Figs. 2 and 3 by numerals 64, which is wound around the extension of the pivot pin 50 and has one end 64a pressing against the wall of the casing beneath the operating lever 42 and its other end pressing against a lug 60b bent up at right angles to the plane of the member 60. The member 60 is pivotally connected by a pin 66 to one end of the link 62. This link 62 comprises a pair of sheet metal stampings each having one end offset from the other (see Figure 4) by means of a double right angle bend formed in the center of the stampings. One stamping is placed on one side and one on the other side of the member 60 at the pivot pin 66 with the offset ends of stampings 40 spaced apart from each other, as illustrated in Figure 4, so as to straddle the movable contact arm 22b. The link 62 is connected with the movable contact arm 22b by an insulating connection comprising an inverted T-shaped member 70 45 formed from sheet insulating whose leg 70a extends up from the lower side of the contact arm 22b through an aperture in the central portion of said arm and also through an aperture in a small insulating plate 72 placed upon the other 50 side of the contact arm 22b. The arm 70a of this insulating member 70 is provided with an aperture for the reception of a shaft or pin 74 passing transversely through the end portions of the two stampings comprising the link 62.

The contact arm 22b may be biased to open circuit position in which case it will assist the bias of the spring 64 when the automatic mechanism is operated upon the occurrence of overload. Or the contact arm 22b may be biased to closed 60 circuit position in which case the spring 64 will have to be stronger than the bias of the contact arm 22b in order to overcome this bias in causing separation of the contact buttons 24 and 26 when the overload mechanism operates.

From the foregoing it will be observed that when the handle or operating lever 42 is moved to closed-circuit position as illustrated in Figure 2 to cause engagement of the contacts 18 and 20 the automatic releasing mechanism is held from 70 operating the contact arm 22b to cause separation of the overload contacts 24 and 26 solely by reason of the engagement of the nose 60a on the member 60 with the end of the current-responsive latch member 33. If, while the parts are 75

held by manual pressure in the position shown in Figure 2, an overload should occur the heat generated in the bimetallic members 30 and 36 will cause clockwise warping and disengagement of the latch member 33 from the nose 60a whereby the operation of the spring 64 is given effect to cause rotation of the member 60 in a clockwise direction and movement of the link 62 to pull the contact arm 22b and contact 24 away from the fixed circuit breaker contact 26 whereby the circuit is automatically interrupted irrespective of whether or not the manually controlled contacts 18 and 20 are held in engagement.

It should be observed that upon release of the handle or operating lever 42, the spring 48 will move the handle to the position shown in Figure 1 and in case the circuit has been automatically interrupted and the parts are in the position shown in Figure 5, will cause the insulating washers 46 to engage with the knee of the linkage connection 60, 62 tending to align the links 60 and 62 and hence move the link 60 in a counter-clockwise direction to again engage the nose 60a with the end of the latch member 33. Thus the device automatically resets itself upon the release of the handle to open circuit position. The operating lever 42 is a free member having no permanent connection with either the overload mechanism or the contact arm 22a, but, it causes operation of those parts merely by abutment against them.

From the foregoing it will be apparent that I have devised a circuit interrupter of a small number of parts which may be inexpensively manufactured and which will be accurate and positive in operation. It will also be noted that the circuit may not be held closed by continued pressure upon the operating handle while the overload persists in the circuit.

Many modifications within the scope of my invention will occur to those skilled in the art, therefore I do not limit myself to the specific form of the embodiment disclosed.

I claim:—

1. In a circuit interrupter, fixed and movable manually controlled contact members, fixed and movable automatically controlled contact members operable independently of the manually controlled contact members, mechanism for engaging and disengaging said automatically operable members comprising a plurality of pivotally connected links one of which is connected to said movable automatically operable contact member, means operated by the occurrence of an overload 50 in the circuit to release said link mechanism, and a hand lever for moving said manually controlled contact members into engagement, said lever engaging directly with said manually movable contact member upon operation in one direction and directly with said link mechanism upon movement in the other direction, whereby said link mechanism may be reset.

2. In a circuit interrupter, fixed contact members, resiliently mounted movable contact members engageable with different fixed contact members, one of said movable contact members being manually controlled, the other of said movable contact members being automatically controlled, a hand lever, mechanism automatically operable upon occurrence of an overload current to cause said automatically controlled contact member to disengage its fixed contact member, said mechanism including a plurality of pivotally connected links one of which is pivotally connected to said automatically controlled movable contact member and another being mounted on a fixed pivot, said lever engaging with said manually movable contact member upon movement in one direction but being disconnected from said manually movable contact member whereby upon movement in the other direction said lever may engage with said automatic mechanism to reset it, and means biasing said manually movable contact member

movable contact member and another being mounted on a fixed pivot, said lever engaging with said manually movable contact member upon movement in one direction and with said automatic mechanism upon movement in the other direction whereby to reset said automatic mechanism.

3. In a circuit interrupter, fixed contact members, resiliently mounted movable contact members engageable with different fixed contact members, one of said movable contact members being manually controlled, the other of said movable contact members being automatically controlled, a hand lever having a pivotal mounting independent of said movable contact members, mechanism automatically operable upon the occurrence of an overload current to cause said automatically controlled contact member to disengage its fixed contact member, said mechanism including a plurality of pivotally connected links one of which is pivotally connected to said automatically controlled movable contact member and another being mounted on a fixed pivot, said lever engaging with said manually movable contact member upon movement in one direction and with said automatic mechanism upon movement in the other direction whereby to reset said automatic mechanism, and means biasing said manually movable contact member out of engagement with its fixed contact member.

4. In a circuit interrupter, fixed contact members, resiliently mounted movable contact members engageable with different fixed contact members, one of said movable contacts being manually controlled, the other of said movable contact members being automatically controlled, a hand lever having a pivotal mounting independent of said movable contact members, mechanism automatically operable upon the occurrence of an overload current to cause said automatically controlled contact member to disengage its fixed contact member, said mechanism including a plurality of pivotally connected links one of which is pivotally connected to said automatically controlled movable contact member and another being mounted on a fixed pivot, said lever engaging with said manually movable contact member upon movement in one direction but being disconnected from said manually movable contact member whereby upon movement in the other direction said lever may engage with said automatic mechanism to reset it.

5. In a circuit interrupter, fixed contact members, resiliently mounted movable contact members engageable with different fixed contact members, one of said movable contact members being manually controlled, the other of said movable contact members being automatically controlled, a hand lever having a pivotal mounting independent of said movable contact members, mechanism automatically operable upon the occurrence of an overload current to cause said automatically controlled contact member to disengage its fixed contact member, said mechanism including a plurality of pivotally connected links one of which is pivotally connected to said automatically controlled movable contact member and another being mounted on a fixed pivot, said lever engaging with said manually movable contact member upon movement in one direction but being disconnected from said manually movable contact member whereby upon movement in the other direction said lever may engage with said automatic mechanism to reset it, and means biasing said manually movable contact member

out of engagement with its fixed contact member.

6. In a circuit interrupter, fixed contacts, a unitary contact member having independently movable portions engageable with different fixed contacts, means automatically operated by the occurrence of an overload current to cause disengagement of one of said movable portions from its fixed contact, a hand lever movable in one direction to engage with the other movable portion and to cause engagement of it with its fixed contact, said hand lever when moving in the opposite direction engaging said automatic mechanism to reset it.

7. In a circuit interrupter, fixed contacts, a unitary contact member having independently movable portions engageable with different fixed contacts, means automatically operated by the occurrence of an overload current to cause disengagement of one of said movable portions from its fixed contact, a hand lever having a lost-motion connection with the other movable portion and causing it upon movement in one direction to engage with its fixed contact, said hand lever when moving in the opposite direction engaging said automatic mechanism to reset it.

8. In a circuit interrupter, fixed contacts, a unitary contact member having independently movable portions engageable with different fixed contacts, means automatically operated by the occurrence of an overload current to cause disengagement of one of said movable portions from its fixed contact, a hand lever having a lost-motion connection with the other movable portion and causing it upon movement in one direction to engage with its fixed contact, said hand lever when moving in the opposite direction engaging said automatic mechanism to reset it, and means biasing said manually movable portion out of engagement with its contact.

9. In a circuit interrupter, fixed contacts, movable contacts, a hand lever movable to cause one of said movable contacts to engage a fixed contact, a link connected to a second movable contact, said second movable contact being engageable with a second fixed contact, a member pivotally connected to said link, means biasing said second movable contact out of engagement with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the first-mentioned movable member.

10. In a circuit interrupter, fixed contacts, movable contacts, a hand lever movable to cause one of said movable contacts to engage a fixed contact, a link connected to a second movable contact, said second movable contact being engageable with a second fixed contact, a member pivotally connected to said link, means biasing said second movable contact out of engagement with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the first-mentioned movable member, and means biasing said hand lever into open-circuit position, said hand-lever-biasing means being of sufficient strength to cause the re-engagement of said holding means and said member to be automatic when the hand lever is relieved of manual pressure.

and said member to be automatic when the hand lever is relieved of manual pressure.

11. In a circuit interrupter, fixed contacts, a unitary contact member having movable portions, contacts on said portions adapted to engage and disengage with different fixed contacts, a hand lever movable to cause one of said movable contacts to engage a fixed contact, a link connected to move a second movable contact, said second movable contact being engageable with a second fixed contact, a member pivotally connected to said link, means biasing said second movable contact out of engagement with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the first mentioned movable member.

12. In a circuit interrupter, fixed contacts, a unitary contact member having movable portions, contacts on said portions adapted to engage and disengage with different fixed contacts, a hand lever movable to cause one of said movable contacts to engage a fixed contact, a link connected to move a second movable contact, said second movable contact being engageable with a second fixed contact, a member pivotally connected to said link, means biasing said second movable contact out of engagement with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the first mentioned movable member.

13. In a circuit interrupter, fixed contacts, movable contacts, a freely mounted hand lever having no permanent connection with said movable contacts, said hand lever being movable to cause one of said movable contacts to engage a fixed contact, a link connected to a second movable contact, said second movable contact being engageable with a second fixed contact, a member pivotally connected to said link, means biasing said second movable contact out of engagement with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the first-mentioned movable member.

14. In a circuit interrupter, fixed contacts, movable contacts, a freely mounted hand lever having no permanent connection with said movable contacts, said hand lever being movable to cause one of said movable contacts to engage a fixed contact, a link connected to a second movable contact, said second movable contact being engageable with a second fixed contact, a member pivotally connected to said link, means biasing said second movable contact out of engagement with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the first-mentioned movable member.

ment with said second fixed contact, thermally responsive means releasable by the action of an overload current and normally holding said second movable contact in engagement with said second fixed contact against the bias of said biasing means, said hand lever causing re-engagement of said holding means and said member upon the movement of said lever away from the

first mentioned movable member, and means biasing said hand lever into open-circuit position, said hand-lever biasing means being of sufficient strength to cause the re-engagement of said holding means and said member to be automatic when the hand lever is relieved of manual pressure.

MONROE GUETT.
